EXPLOSIVE PROJECTILE

Wilfred E. Thibodeau, Cleveland, Ohio

Application February 6, 1941, Serial No. 377,600

1 Claim. (Cl. 102—56)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to projectiles in general and in particular to small arms and medium explosive projectiles.

The limited space in these types of projectiles and the cost of manufacture will as a general rule, prohibit the use of firing devices such as the cumbersome fuses known in the projectile art. The need is for simplicity of design, minimum number of parts and low cost of manufacture consistent with safety and fidelity of operation. A further desideratum is ease of assembly, and it is highly convenient and safe to load priming units separately for ultimate insertion into the projectile.

The projectile of the invention accomplishes these designs by incorporating in a projectile a simple firing device consisting of an inertia-firing member placed in juxtaposition with detonating material without any of the usual safety barrier members restraining against its inertial progress in handling or on impact. The firing member is restrained however as to motion in directions other than that necessary for detonation on impact. That is to say, it is supported laterally by the inner walls of the projectile while being left free of any unyielding barriers in the direction of the projectile axis and is held snugly during ordinary handling by the packed detonating material. The ease and safety of assembly provided will be clear as the description proceeds.

It is therefore an object of this invention to produce a projectile having a simple inertia firing member in contact with and restrained only by the detonating material in the direction of the axis of the projectile and in contact with and receiving lateral support from the inner walls of the projectile.

It is a further object of the invention to provide a compound projectile affording ease of assembly of the priming units.

To these and other ends, the invention consists in the construction, arrangement and combination of elements described hereinafter and pointed out in the claim forming a part of this specification.

A practical embodiment of the invention is illustrated in the accompanying drawing wherein:

Figure 1 is an elevation in section of the forward portion of a projectile, and

Figures 2, 3 and 4 are views similar to Figure 1 showing modifications.

Referring to the drawing by characters of reference there is shown in Figure 1 a main projectile body 1 surrounded by a jacket 2 having an ogival portion 3 and rearwardly seated on a shoulder 4 of body 1. The truncated forward face 5 of body 1 has a central bore 6 and in this bore is snugly fitted a cylindrical pin 7 with hemispherical ends 8 and 9.

Between the face 5 and the inner walls of the ogive 3 is a space 10 into which the outer portion 8 of pin 7 protrudes. Surrounding the head 8 and filling the space 10 is the detonating material 11.

Inside body 1 is a cavity 12 containing a main explosive charge 13. Also in cavity 12 and surrounding the inner end 9 of pin 6 is a further quantity of detonating material 11, although this may be omitted.

The bore 6 will steady pin 7 against all lateral disturbances and the detonating material closely packed about the ends of pin 6 will support the pin in the longitudinal directions. When properly packed, this detonating material will not be set off by disturbances of the firing pin in ordinary handling, due to its packing, the small mass of the pin and the smooth contours of the pin ends. On impact after firing, however the force is sufficient to detonate and this detonation is supplemented by the percussion of that portion of the detonating material behind the pin, which is set off by stoppage of the pin.

In assembling the projectile, the detonating material 11 is first packed into the nose of the jacket 2. In this operation a space may or may not be left to accommodate the outer end 8 of pin 7. If the space is not left, the pin is later forced in. The shell cavity 12 is then loaded with explosive 13, topped with detonating material and the pin inserted in bore 6. Assembly is then virtually completed by placing the body member 1 into the jacket 2 and fixing the two by any appropriate means.

In Figure 2 is shown a modification of the firing member. Here the striker 14 has been fore-shortened to bring the hemispherical ends of the striker together to form a sphere. The lateral support of the striker by the projectile walls has been retained, however.

In Figure 3 is shown a modification of the striker and of the primer. Here the striker 15 is constructed along the lines of the front portion only of the striker 7 of Figure 1, the rear detonating material has been omitted and a booster 16 substituted therefor, and the detonating ma-

terial 11 is contained in a separate capsule 17 snugly fitting the inside of the ogive.

This form of the invention offers an advantage in respect to the loading of the projectile body proper, since the detonating material has been omitted therefrom together with the necessary step of carefully packing the same. The provision of a separate capsule for the detonating material in the nose portion solves a problem of assembly and production. In prior art explosive 10 bullets, the priming had to be packed into a complete bullet whereas in the present case this loading is performed on a separate capsule and the latter simply placed into the bullet at will. They may thus be stored prior to assembly, and defective loadings are more easily detected, and less 15 expensive and time-consuming consequences ensue therefrom. Furthermore, since the making of the projectile and packing of the primer are performed separately, there will be a tendency 20 to avoid bottlenecks in production.

In Figure 4 is shown a projectile with a main body portion 18 having an inwardly flanged end portion 19 with central opening 20 countersunk as at 21 to provide a seat for the spherical 25 striker 22.

Tightly fitted in an axial bore 23 in the nose of jacket 24 is a pin 25 of solder or other easily

fusible or heat destructible material such as a mixture of refractory and carbonaceous materials, as disclosed in application Serial Number 375,379 filed January 22, 1941, now Patent Number 2,314,891. Between the sphere 22 and the jacket 24 is the packed detonating material 11. Since the pin 25 contacts the sphere 22, the latter is held in its seat 21. There is thus furnished an additional safety against detonation in the event of accidental shocks prior to firing. On firing, the resistance offered by pin 25 will dissipate due to the heat generated by friction of the projectile with the gun barrel and with the air in flight.

I claim:

In a hollow projectile, a radially inward constriction of the inner walls thereof defining an axial throat relatively narrow with respect to the hollow portion, said constriction separating the inner portion of the projectile into a large rear chamber and a small forward chamber, a metallic sphere slidably fitted in said throat in contact with the sides thereof, a main explosive charge in said rear chamber spaced from said sphere, and a detonating charge completely filling the available space in said forward chamber, and filling the space between said main charge and said sphere.

WILFRED E. THIBODEAU.
